Primary Examiner—Charles A Rademaker*(74) Attorney, Agent, or Firm*—Jacobson Holman PLLC(57) **CLAIM**

The ornamental design for a stamp pad, as shown and described.

DESCRIPTION

FIG. 1 is a front elevation of the stamp pad, according to my novel design;

FIG. 2 is a rear elevation thereof;

FIG. 3 is a left elevation thereof;

FIG. 4 is a right elevation thereof;

FIG. 5 is a top plan view thereof;

FIG. 6 is a bottom view thereof;

FIG. 7 is a cross-section thereof taken along a line A—A in FIG. 5;

FIG. 8 is a cross-section thereof taken along a line B—B in FIG. 1;

FIG. 9 is a cross-section thereof taken along a line C—C in FIG. 1;

FIG. 10 is a front elevation of the un-locked stamp pad, according to my novel design;

FIG. 11 is a rear elevation thereof;

FIG. 12 is a left elevation thereof;

FIG. 13 is a right elevation thereof;

FIG. 14 is a top plan view thereof;

FIG. 15 is a bottom view thereof;

FIG. 16 is a perspective view thereof taken upper, right and frontward;

FIG. 17 is a perspective view thereof taken lower, left and frontward; and,

FIG. 18 is a perspective view thereof of the lid-opened stamp pad taken upper, right and frontward.
